(57) **CLAIM**

The ornamental design for a handle, as shown and described.

DESCRIPTION

FIG. 1 is a perspective view of a handle showing our new design;

FIG. 2 is a top view thereof;

FIG. 3 is a bottom view thereof wherein the broken lines do not form a part of the claimed invention;

FIG. 4 is a front elevational view wherein, due to the cylindrical nature of the invention, the front elevational view is identical to the back elevational view; and,

FIG. 5 is a left elevational view wherein, due to the cylindrical nature of the invention, the left elevational view is identical to the right elevational view.

1 Claim, 2 Drawing Sheets

FIG. 1
